UNITED STATES PATENT OFFICE

108,216

DESIGN FOR A LAMP STAND

Morris Ozlek, Philadelphia, Pa.

Application April 9, 1937, Serial No. 68,648

Term of patent 7 years

To all whom it may concern:

Be it known that I, Morris Ozlek, a citizen of the United States, residing at Philadelphia, in the county of Philadelphia and State of Pennsylvania, have invented a new, original, and ornamental Design for Lamp Stands, of which the following is a specification, reference being had to the accompanying drawing, forming part thereof. The dominant features of the design are shown in full lines.

The figure is a perspective view of a lamp stand, showing my new design.

I claim:

The ornamental design for a lamp stand, as shown.

MORRIS OZLEK.
